L. M. BOWMAN

TOY PISTOL

Filed Dec. 16, 1922

Inventor
LEM M BOWMAN

By A. L. Jackson
Attorney

UNITED STATES PATENT OFFICE

LEVI M. BOWMAN, OF FORT WORTH, TEXAS, ASSIGNOR TO OTTO H. LANG, TRUSTEE,
OF DALLAS, TEXAS.

TOY PISTOL.

Application filed December 16, 1922. Serial No. 607,321.

To all whom it may concern:

Be it known that I, LEVI M. BOWMAN, a citizen of the United States, residing at Fort Worth, in the county of Tarrant and 5 State of Texas, have invented certain new and useful Improvements in Toy Pistols, of which the following is a specification.

My invention relates to toy pistols; and the object is to provide a simple toy which 10 can be furnished at small cost and which will afford much amusement as a plaything and to make use of discarded wooden ends or blocks of furniture factories and thus make use of such discarded material as a 15 valuable by-product. Other objects and advantages will be fully explained in the following description and the invention will be more particularly pointed out in the claim.

20 Reference is had to the accompanying drawings which form a part of this application.

Fig. 1 is a side elevation of the pistol, partly in section. Fig. 2 is a plan view of 25 the same. Fig. 3 is a horizontal section of the frame, taken on the line 3—3 of Fig. 1, showing the location of certain parts of the discharging mechanism. Fig. 4 is a broken vertical section, taken on the line 30 4—4 of Fig. 1.

Similar characters of reference are used to indicate the same parts throughout the several views.

The toy is provided with a main frame 1 having a barrel portion and a handle. A longitudinal opening 2 through the main portion serves as a barrel for BB shot 3 and a magazine 4 is provided for the BB shot 3 in the upper part of the barrel portion 35 so that the shot may be fed automatically down through an opening 5 in the barrel 2. A discharge plunger or shot thrower 6 is mounted in a longitudinal opening in the frame portion 1. This 40 plunger is limited in the outward motion by a shoulder 20 and the hammer portion 21 projects into the barrel proper. The device is also provided with a trigger plunger 7 which is partly cylindrical and has depending from the cylindrical portion a trigger 22. The frame has a cylindrical longitudinal opening for the plunger 7 and a slot 23 for the trigger 22. Means are provided for operatively connecting the shot 45 plunger and the trigger plunger. A trip 50 55 60 65 70 75 80 85 90 95 100 105 110

10 is pivotally mounted in a slot 24 in the plunger 7 by means of a pivot pin 11. The trip has a spur 25 which engages a notch in the end 6 of the shot plunger for causing the shot plunger to move backwardly as the trigger plunger is forced backwardly by the finger of the operator. The frame 1 has a horizontal slot 8 for the shot plunger actuating means which consisting of a piece of elastic or rubber 12 is passed around the rear end of the plunger in a recess 27 in the end of the plunger and the ends of the rubber are attached to the sides of the frame at 26. The plunger is forced backwardly against the tension of the rubber or elastic 12. The rear end of the trigger plunger 7 has a similar recess 28 and a similar piece of rubber 12 is used in the same manner as on the shot plunger. The plunger 7 is cut away at 29 and a piece of rubber band 30 normally holds the inner end of the trigger 10 down in the slot 24. Means are provided for releasing the trigger 10 from the plunger 6. A pin 9 is run through the frame 1 and intercepts the slot in the frame 1 and when the beveled portion 31 of the trip 10 strikes the pin 9, the spur 25 will be drawn out of the notch in the plunger 6. This will release the shot plunger 6 and the hammer 21 will throw the shot 3. Both plungers will be thrown forward by the rubber or elastic 12. A detachable lid 32 closes the magazine 4. The pistol may be provided with a sight 16. A guard 15 prevents displacement of the trigger 22 and plunger 7 in their forward movement. A slot 33 is made in the side of the frame 1 and a spring 13 is provided for preventing the shot 3 which has been dropped into the barrel 2 from being displaced or from rolling in the barrel. The spring 13 is attached at one end to the body and the other end bears loosely against the shot 3 merely to keep the shot from rolling out of place. A shot will drop in the channel 2 as the plunger 21 is drawn back before the spring 13 comes back into the channel. The spring 13 will not interfere with the discharge of the shot by the hammer 21. When the operator releases the trigger 22, the elastic or rubber 15 will return the trigger plunger to normal position and at the same time cause the spur 25 to engage the plunger 6.

What I claim, is,—

A toy pistol comprising a trigger plunger 110

- and a discharge plunger, a trip pivoted in said trigger plunger and operatively engaging said discharge plunger, elastic means normally holding said trip in engagement with said discharge plunger, a frame for said plungers having a longitudinal bore therein forming a barrel for said discharge plunger and a longitudinal slot for said trigger plunger and having a magazine in 5
10 the upper part for containing shot and for feeding shot one at a time to said barrel, means for preventing premature displacement of a shot in said barrel, means for automatically releasing said trip from said discharge plunger when the trigger is forced 15 backwardly by the operator, resilient means for actuating said discharge plunger when released from said trip, and means for restoring said trigger plunger to normal position and for causing said trip to engage 20 said discharge plunger.

In testimony whereof, I set my hand, this 11th day of December, 1922.

LEVI M. BOWMAN.
